United States Patent Office

Des. 225,367
Patented Dec. 5, 1972

225,367

RING

Warren R. Higgins, 4764 N. Oakland Ave.,
Milwaukee, Wis. 53211

Filed Mar. 8, 1971, Ser. No. 122,256

Term of patent 14 years

Int. Cl. D11—01

U.S. Cl. D45—10

FIG. 1 is a side view of a ring showing my new design;
FIG. 2 is an edge view thereof;

FIG. 3 is a cross-sectional view of the ring taken on
the lines 3—3 of FIG. 1; and

FIG. 4 is a developed plan view thereof showing the
complete surface ornamentation thereon.

I claim:

The ornamental design for a ring, as shown and de-
scribed.
